SAFETY RAZOR AND SAFETY RAZOR BLADE CLAMP

Alfred William Brenninger, Philadelphia, Pa.

Application June 10, 1943, Serial No. 490,364

7 Claims. (Cl. 30—51)

1

This invention relates to safety razors and more particularly to an improved safety razor blade clamp.

It is a primary object of the present invention to provide a safety razor which requires a minimum of metal.

Another object of the invention is to provide a safety razor which is relatively inexpensive to manufacture.

Another object of the invention is to provide a safety razor having a blade which can be quickly and easily detached from and secured to the holder.

Another object of the invention is to provide a safety razor having a minimum number of parts.

Another object of the invention is to provide a safety razor which is easily cleaned.

Another object of the invention is to provide an improved safety razor blade requiring a minimum of metal and which can be easily manufactured in quantity production.

According to the invention, the blade holder, comprises a handle and a generally rectangular blade support part having the usual guard serrations at the forward edge, the blade support part being inclined to the handle. The blade is of non-perforated rectangular form and is relatively narrow. The blade is clamped within a narrow metal element extending substantially the length of the blade and generally U-shaped in cross section. This element is formed to detachably engage the blade holder. In one form of the invention, the ends of the blade support part of the holder and the clamp element have inter-engaging tongues and grooves for mounting the clamp element on the holder. In another form of the invention, the blade support part has a longitudinally extending flange adapted to project within a generally U-shaped groove formed in the blade clamping element.

The nature and advantages of my invention will become increasingly apparent from a consideration of the following description and drawings, wherein:

Fig. 1 is a perspective view of a blade holder I may employ;

Fig. 2 is a plan view of the holder of Fig. 1 with a blade and blade clamp element mounted thereon;

Fig. 3 is a cross sectional view of the blade and blade clamp element illustrated in Fig. 2 taken along the line 3—3;

Fig. 4 is a plan view of a modified holder, modified blade clamp element, and blade I may employ;

2

Fig. 5 is a longitudinal sectional view of the blade and blade clamp element illustrated in Fig. 4 taken along the line 5—5;

Fig. 6 is a plan view of a further modified holder, modified blade clamp element, and blade I may employ;

Fig. 7 is a side elevational view of the holder of Fig. 6;

Fig. 8 is a section of the blade clamp element and blade shown in Fig. 6 taken along the line 8—8;

Fig. 9 is a cross-sectional view of a double-edge blade and blade clamp element generally similar to the blade clamp element illustrated in Fig. 3;

Fig. 10 is a plan view of a double-edge blade and blade clamp element generally similar to that illustrated in Fig. 5;

Fig. 11 is a fragmentary perspective view of the blade holder illustrated in Fig. 4; and

Fig. 12 is a partial longitudinal section taken along line 5—5 of Fig. 4 showing relation of the blade, blade clamp element, and blade support part.

Referring now to the drawings, and more particularly to Figs. 1, 2, and 3, the blade holder indicated generally at 10 comprises a blade support part 11 and a handle 12. The blade support part, preferably formed of metal, is generally rectangular in shape and has a serrated or slotted forward edge forming the usual fingers 13 inclined downwardly at the ends to a desired angle providing smooth contact with the skin of a user.

At each end of the forward edge of the blade support part 11 is a hook form finger 14 providing upstanding abutments for engaging the forward or cutting edge of the blade. Each end of part 11 is recessed to form rectangular grooves 16 for engaging down-turned tongues 17 of the blade clamping element 18. The blade is relatively narrow, the width being preferably 25 per-cent or less of the blade length. The blade clamp element 18 is preferably formed of thin sheet metal and is of U form in cross section to receive and grip the blade with the cutting edge of the blade, indicated at 19, extending beyond the element.

The confronting faces of depending tongues 17 are normally spaced apart longitudinally a slightly less distance than the longitudinal distance between the grooves 16 of support part 11 so that it is necessary to slightly spread the ton-

gues longitudinally when positioning the clamp element and blade on the holder.

To engage the blade and clamping element with the part 11 it is only necessary to position the cutting edge of the blade against the abutments 14 and rock the blade downwardly to spring the tongues 17 into grooves 16. The resilience of the tongues insures that the blade will be maintained in proper engagement with the holder during use of the razor. The rear edge of the tongues engage the rear edge of the grooves so that backward movement of the blade relative to part 11 is prevented and relative forward movement is restrained by the abutments 14. For ease in gripping the blade for mounting on or removal from the holder I provide a rounded recess 21 in the rear edge of part 11.

Any suitable handle may be provided for part 11 and in the holders illustrated the handle is permanently secured at an angle of approximately 60 degrees although it is understood that the handle may be detachably secured and the relative angularity between part 11 and the handle may be altered as desired. In the holders illustrated a metal shank 22 has a reduced stem which is projected through part 11 and is flush with the top surface thereof. The shank may be soldered or otherwise secured to part 11. The lower end of the shank has a reduced portion pressed into a hole in the gripping portion 23 of the handle. Portion 23 may be formed of synthetic resin or other suitable materials and is preferably hexagonal in cross-section or serrated to prevent rotation or slipping while gripped.

In Figs. 4, 5, and 11 I have illustrated a modified form of safety razor generally similar to the razor illustrated in Figs. 1 to 3 inclusive but in this construction grooves 24 are formed in the blade clamping element and upstanding tongues 26 are provided at the ends of the blade support part for engaging the grooves. The tongues are preferably very slightly less in width than the grooves. Abutments 27 at each end of the blade support part 28 engage the cutting edge of the blade. These abutments and abutments 14 shown in Fig. 1 are substantially flush with the top surface of the blade. The upstanding tongues 26 grip the blade clamping element frictionally at the grooves 24 to maintain the blade and clamping element seated on the holder support part during use of the razor. This may be effected by inclining the tongues slightly towards each other so that the tongue ends are normally slightly closer together than the longitudinal distance between the grooves 24 so that the tongues will be forced slightly apart when positioning the blade and clamp element on the holder.

The blade clamping element 29 is U form in longitudinal cross-section and as illustrated in Fig. 5 the end portions are extended beyond the blade 25 and preferably crimped at the ends 30 remote from the U bend to secure the blade 25 to the element 29.

In the modification illustrated in Figs. 6 to 8 inclusive the blade support portion 31 is reversely bent to provide a longitudinally extending flange 32. The blade clamping element has a portion 33 of U cross-section which clamps the blade and a reversely bent portion 34 forming a groove 35. The blade is mounted by pressing flange 32 within groove 35, the flange 32 is curved and portion 34 is similarly curved to seat on the flange when the blade is properly mounted. Portion 33 of the blade clamping element preferably makes a rela-

tively tight sliding contact with flange 32 and the base 37 of the blade mounting portion.

Fig. 9 illustrates a blade generally similar to the blade illustrated in Fig. 3 but in this modification the blade is provided with two cutting edges 38 and 39. The blade clamping element may comprise an upper part having down-turned end tongues 42 and a lower part 43 press-fitted between tongues 42.

Fig. 10 illustrates a blade generally similar to the blade shown in Fig. 5 but wherein double cutting edges are provided. The blade clamping element 44 may comprise a single strap of U form longitudinally with the strap ends crimped together at 46 to secure the blade. Grooves 47 are formed in the clamping element ends to engage upstanding tongues on the holder.

The blades described which comprise the blade proper and the blade clamping element require a relatively small amount of metal, the blade proper and clamping element can be economically and easily assembled, and the blade can be easily cleaned. The blade can be quickly mounted on and removed from the holder and will remain in proper operative position during use of the razor.

It will be understood that in the various modifications disclosed with the exception of the modification illustrated in Figs. 6 to 8 inclusive that due to the relative spacing of the interengaging tongues and grooves endwise pressure is exerted on or by the tongues when the blade and clamp element are positioned on the holder.

The blades formed by the clamping element 35 and blade proper have been shown as comprising two parts but it is understood that they may be formed as a single part, and particularly the blades illustrated in Figs. 2 and 4.

Although I have shown and described preferred forms of my invention I contemplate that numerous and extensive departures may be made therefrom without departing from the spirit of my invention and the scope of the appended claims.

What I claim is:

1. A safety razor comprising a blade support part, a blade, a blade clamp element including top and bottom plies engaging the top and bottom surfaces of the blade, the blade support and blade clamp element having interengaging tongue and recess portions formed at the ends thereof, and the tongue portions being resilient and normally spaced to be forced slightly apart upon engagement with the recess portions whereby the blade and clamp element are detachably secured to the support.

2. A safety razor comprising a generally rectangular blade support having upstanding abutments at the forward edge thereof and recessed end portions, a blade, a blade clamp element including top and bottom plies engaging the top and bottom surfaces of the blade and substantially co-extensive in length with the blade, the blade cutting edge extending forwardly of the clamp element, the clamp element having depending resilient tongues at each end thereof normally spaced apart slightly less than the distance between the recessed portions, and the blade and clamp element being detachably secured to the support by engaging the blade cutting edge with the support abutments and disposing the clamp element tongues within the recessed portions of the support whereby the tongues grip the support with endwise pressure.

3. A safety razor comprising a blade holder including a generally rectangular blade support and

a handle extending therefrom, the support having recessed end portions and a rounded recess in the rear edge thereof, a blade, a blade clamp element including top and bottom plies engaging the top and bottom surfaces of the blade and depending resilient tongues at each end thereof adapted to seat at the recessed end portions of the support, the tongues being normally spaced to be forced slightly apart and exert endwise pressure on the support when seated and the clamp element overlying the said rounded recess whereby the clamp element may be gripped for detachment of the clamp element and blade from the holder.

4. In a safety razor comprising a blade holder having a flat blade support the subcombination comprising a generally rectangular blade, a clamp element including top and bottom plies engaging the top and bottom surfaces of the blade and extending slightly beyond the blade ends, the blade cutting edge extending forwardly of the clamp element, the clamp element having resilient tongues extending angularly from each end thereof adapted to detachably engage said blade holder, and the tongues being normally spaced relative to the holder to exert endwise pressure on the holder when engaged therewith.

5. In a safety razor comprising a flat blade support with a resilient upstanding tongue at each end for gripping a blade and clamp element, the combination comprising a generally rectangular blade, a clamp element including top and bottom plies engaging the top and bottom surfaces of the blade and extending slightly beyond the blade ends, the blade cutting edge extending forwardly of the clamp element, the clamp element having recessed end portions adapted to seat said resilient tongues of the blade support, and the recessed portions being spaced to slightly spread the tongues when seated.

6. A safety razor comprising a holder having

a generally rectangular support part and a handle, a resilient tongue extending from the upper surface of the support part, a blade, a blade clamp element having plies overlying the upper and lower surface of the blade to leave the blade cutting edge exposed, the clamp element having a portion adapted to receive the support tongue, and the tongue being formed to exert resilient pressure against said clamp element receiving portion when the blade and clamp element are seated on the holder to grip the clamp element between said tongue and a portion of the holder spaced from the tongue.

7. A safety razor comprising a holder having a generally rectangular support part and a handle, a blade, a blade clamp element having plies overlying the upper and lower surface of the blade to grip the blade and leave the blade cutting edge exposed, and the support part and clamp element having interengaging portions with at least one of said portions being resilient and adapted to exert frictional pressure against its associated portion when engaged therewith whereby the clamp element and blade may be seated upon and removed from the support part solely by manual pressure.
